Specification for Design.

Patented May 10, 1921.

Application filed October 30, 1920. Serial No. 420,815. Term of patent 14 years.

To all whom it may concern:

Be it known that I, GEORGE D. GORDON, a citizen of the United States, residing at Philadelphia, in the county of Philadelphia and State of Pennsylvania, have invented a new, original, and ornamental Design for a Rear-End Signal Device for Automobiles, of which the following is a specification.

Referring to the drawing—

Figure 1 is a front elevation of my rear end signal device for automobiles, showing my new design;

Fig. 2 is a top plan view;

Fig. 3 is an end view.

I claim:

The ornamental design for a rear end signal device for automobiles, substantially as shown.

In testimony that I claim the foregoing as my own I have hereto affixed my signature.

GEORGE D. GORDON.

Witness:
